Goldstein & Fox P.L.L.C.(57) **CLAIM**

The ornamental design for a drinking vessel, as shown and described.

DESCRIPTION

FIG. 1 is a top front perspective view of a first embodiment of a drinking vessel showing our new design;

FIG. 2 is a bottom front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top front perspective view of a second embodiment of a drinking vessel showing our new design;

FIG. 10 is a bottom front perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The dashed broken lines in the figures show portions of the drinking vessel that form no part of the claimed design.

The dot-dash broken lines in the figures show boundaries that form no part of the claimed design.

1 Claim, 14 Drawing Sheets(56)
